SHOE POLISHING DEVICES

Rufus R. Rand, Minneapolis, Minn.

Application June 16, 1955, Serial No. 515,878

1 Claim. (Cl. 15—258)

This invention relates to new and useful improvements in shoe polishing devices, and particularly to such a device which may readily be carried about in a suitcase, traveling bag, or in a pocket.

An important object of the present invention is to provide a small compact shoe shining kit, which includes the necessary polishing paste or material, an applicator for applying such material to the surface of a shoe in a uniform film, and a suitable polishing cloth or strip for polishing the shoe after the polishing paste or other polishing material has been applied thereto.

A further object of the invention is to provide a pocket size shoe shining and dressing kit, comprising a plurality of disposable pads for applying shoe paste to the surface of a shoe, and each such pad having a limited quantity of polishing paste or material applied to a small area thereof, said pads being formed of a suitable material such as paper, plastic and paper, cellulose tissue, or other material applicable for the purpose, to one side surface of which the polishing paste or material is directly applied, and the opposite side surface of each pad being treated or coated with a suitable moisture resistant material adapted to be engaged by the fingers, when applying the polishing paste to a shoe to prevent the paste from penetrating through the applicator pad and soiling the user's fingers.

A further object of the invention is to provide a pocket size shoe shining and dressing kit comprising a plurality of shoe polishing paste secured thereto, and said pads originally being interconnected to form an elongated continuous strip adapted to be coiled into a small compact roll, and said strip being transversely scored or perforated at equidistant points along the length thereof to define said pads, and to provide tear lines between adjacent pads, whereby the pads may readily be torn from the strip, one at a time, when it is desired to polish a pair of shoes or other article.

A further and more specific object of the invention resides in the unique manner in which the wads or wafers of polishing paste are located on the strip of connected paste-applying pads, whereby when the strip of pads is coiled into a small roll, the wafers of polishing paste thereon will not overlap one another.

Other objects of the invention reside in the simple and inexpensive construction of the polishing kit, as a whole, which include a plurality of disposable applicator pads, each having a small portion of polishing paste secured thereto, and an elongated polishing cloth or member which, in addition to serving as a polishing cloth, also serves as an outer enclosing or covering member for the roll of paste-applying pads, whereby the composite kit may readily be carried in a suitcase, traveling bag, or in a coat pocket without danger of soiling the interior of the bag or pocket, nor the user's fingers; and in the provision of such a polishing kit in which all of the

component parts are made from inexpensive, disposable materials.

These and other objects of the invention and the means for their attainment will be more apparent from the following description taken in connection with the accompanying drawings.

In the accompanying drawings there has been disclosed a structure designed to carry out the various objects of the invention, but it is to be understood that the invention 10 is not confined to the exact features shown, as various changes may be made within the scope of the claim.

In the drawings:

Figure 1 is a perspective view of my improved shoe shining kit, showing the elongated polishing member or 15 cloth wrapped about the roll of applicator pads and polishing paste, as when carried in a traveling bag or pocket;

Figure 2 is a perspective view of the roll of paste applicator pads with the outer polishing cloth removed 20 therefrom, and the roll partially unwound to permit a paste applicator pad to be detached therefrom, and also showing how the paste wafers are located thereon to prevent overlapping of said wafers, when the strip is wound into a roll;

Figure 3 is a perspective view of a paste-applying pad or section detached from the unwound portion of the roll shown in Figure 2;

Figure 4 is a view showing the preferred manner of applying the polishing paste to the surface of a shoe; and

Figure 5 is a view showing the polishing cloth or member removed from the roll of paste-applying pads.

The novel shoe polishing kit herein disclosed is shown comprising an elongated strip of a suitable material such as paper, cellulose tissue, or a combination of paper and 35 plastic, generally designated by the numeral 2. The strip 2 is transversely scored or perforated to provide tear lines 3 at equi-distant points along the length of the strip, thereby to divide it into a plurality of uniform sections or applicator pads 4, which may readily be torn from the 40 strip along the tear lines 3, as indicated in Figure 3.

A feature of the invention resides in the provision on each applicator pad 4, of a small disc or wafer 5 of a suitable shoe polishing paste or material, as best illustrated in Figure 2. The paste wafers 5 are arranged in 45 offset relation lengthwise of the strip, as indicated in Figure 2, so as to prevent the paste wafers from overlapping one another when the strip is coiled into a roll, as illustrated in Figures 1 and 2.

The composition of the polishing paste wafers 5 is such that it will not readily smear or adhere to the opposite side of strip 2 when the strip is coiled into a roll. Its consistency, however, is such that when a section of the strip 2 is torn therefrom, as indicated in Figure 3, and the paste wafer is placed against the surface of a shoe with a slight pressure from the user's fingers, as indicated in Figure 4, the polishing paste may readily be coated over the surface of the shoe in a thin film by gently rubbing the applicator pad 4 over the surface of the shoe, as will be understood by reference to Figure 4.

The side surface of the strip 2 to which the paste wafers 4 are secured, may be somewhat absorbent to permit the paste to penetrate slightly into the surface thereof as the applicator pad is manipulated over the surface of the shoe, thereby to facilitate the operation of uniformly spreading the paste thereover.

The side surface of the strip 2 opposite from the surface on which the paste wafers 5 are applied, is coated with a suitable moisture resistant material to prevent penetration of the polishing paste through the pads 4 onto the user's fingers, when rubbing an applicator pad over the surface of a shoe to apply a film of polishing paste thereto.

Means is provided for enclosing or covering the roll of applicator pads 4, when the latter is not in use, as illustrated in Figure 1. Such means is shown comprising an elongated member 7, preferably of a textile material capable of producing an effective polishing action when rubbed briskly back and forth over the surface of a shoe to which the polishing paste has been applied. The polishing member 7 is of sufficient length to permit the user to grasp the ends thereof and briskly manipulate said member back and forth over the surface of the shoe until a high polish is imparted thereto. If desired, the member 7 may be folded upon itself and used as a rubbing cloth to remove dust and other foreign matter from the surface of a shoe or other article to dress up the appearance thereof.

A strap 8 is secured to one end of the polishing cloth 7, whereby the latter may be inseparably secured in position around the roll 6 of paste applicator pads 4, as illustrated in Figure 1, when the kit is not in use. When the member 7 is thus coiled about the roll 6, the paste wafers are completely enclosed within the composite device whereby the latter may readily be carried in a traveling bag or pocket without any danger of soiling the interiors thereof.

Another important feature of the invention resides in the provision of a shoe polishing kit wherein all of the component parts are made from an inexpensive disposable material, whereby such parts may be discarded or disposed of after use. This is particularly true of the applicator pads 4. The polishing cloth 7 of each composite polishing kit is preferably constructed of a suitable washable material whereby it may be used for several polishing operations before being discarded.

The polishing kit has been found particularly useful to persons traveling from place to place, as it may readily be carried in a pocket or traveling bag, and is always ready for immediate use to dress up a pair of shoes or other articles, such as traveling bags, etc., which may require occasional polishing. Each applicator pad or section 4, when detached from the strip 2 and used in the operation of polishing a pair of shoes is disposed of, it being understood that the quantity of polishing paste contained in each wafer 5 may be sufficient to shine one pair of shoes, or the equivalent thereof. When manipulating the pad 4 over the surface of a shoe, the paste is gradually distributed over the surface of the pad so

that a thin film of paste may be quickly applied to the surface of each shoe, as will be understood by reference to Figure 4.

In the accompanying drawing, Figures 2 and 3, it will be noted that each applicator pad 4 carries but one paste wafer or spot. If it should be desired to widen the range of use of the invention, two paste wafers, one black and the other tan or brown, could be provided on each pad, and so spaced thereon as to avoid overlapping of the paste wafers when the composite strip 2 is coiled into a roll, as illustrated in Figure 1. Such dual paste wafers on each applicator pad would require slightly more care on the part of the user in applying the paste to the shoe surface, in order to avoid intermixing the two different colors of paste.

The foregoing detailed description has been given for clearness of understanding only, and no unnecessary limitations should be understood therefrom, but the appended claim should be construed as broadly as permissible in view of the prior art.

I claim as my invention:

A composite shoe polishing kit comprising an elongated single-ply flexible strip of a porous material transversely scored at uniformly spaced intervals the length thereof, thereby to divide the strip into a plurality of connected applicator pads, the corresponding surfaces of said connected applicator pads each having a wafer of polishing paste secured thereto, said paste wafers being of limited size, and the wafers of adjacent applicator pads being laterally offset from one another lengthwise of said strip, thereby to prevent overlapping of said paste wafers, when the strip is wound into a roll for storage, and an elongated member removably wrapped about said roll to provide a covering member therefor, when the polishing kit is carried in a handbag or pocket, and to serve as a polishing cloth when removed from the roll.
